UNITED STATES PATENT OFFICE.

ALEXANDER CROMBIE, OF BRAIDWOOD, ILLINOIS.

IMPROVEMENT IN COAL-MINING MACHINES.

Specification forming part of Letters Patent No. **179,102**, dated June 27, 1876; application filed May 29, 1876.

To all whom it may concern:

Be it known that I, ALEXANDER CROMBIE, of Braidwood, in the county of Will and State of Illinois, have invented a new and useful Improvement in Machines for Mining Coal and other mineral substances; and I do hereby declare that the following is a full, clear, and exact description of the same, reference being had to the accompanying drawings, forming part of this specification, in which—

Figure 1 is a front elevation of the improved coal-mining machine. Fig. 2 is a top view of the same. Fig. 3 is a vertical transverse section of the same.

The nature of my invention consists in certain constructions, combinations, and arrangements of parts, whereby the mining-machine patented by me December 28, 1875, is greatly improved and simplified, and the cutting-wheel of said machine made capable of cutting its way into the coal-mine, whether it is revolved in a right or left hand direction.

To enable others skilled in the art to understand my invention, I will proceed to describe it.

In the accompanying drawings, A represents the frame of the machine. This frame consists of a long main or bottom platform, A¹, and a short top platform, A². The two platforms are united firmly together by means of a side plate, A³, and pillars or standards A⁴. The frame thus formed is mounted on car-wheels a, which are adapted to run upon the railways used about mines. B is the planing or cutting wheel, applied on the lower end of a vertical revolving shaft, C, which passes up through the platforms A¹ and A², and is confined from lateral movement at its top by the metal of the platform A², and at a point just above the wheel by a strong metal plate screwed firmly to the edge of the platform A¹. This screw-plate might be dispensed with, and the shaft passed up through a hole in the platform A², the same as through the hole in the platform A¹. For preventing any descending movement of the wheel and shaft, a broad bearing collar or shoulder, h, is formed on the shaft just above the platform A¹, and under this collar a steel plate or friction-rollers may be placed. By means of this collar the cutting-wheel B is suspended from the platforms,

and by having the shaft extend through both platforms it is sustained and kept true without the use of any obstruction, such as a lower bearing beneath the wheel for the shaft, and the two separated bearings for the shaft above the wheel, prevent any possible deflection of the wheel, and the main frame proper bears the whole strain of the work done by the cutting-wheel. The cutting-wheel B has right and left rabbets c c' cut in its periphery for cutters d to fit in, and between every pair of which rabbets a concave throat or cavity, e, is formed for the escape of any clogging matters. There are cavities f f cut in the top and bottom faces of the rim of the wheel, into which cutters or plane-irons g are fitted. The seats for the cutters g are made broader than the cutters, in order that clearing-room for obstructing or clogging matter shall be afforded. By changing the periphery cutter d from one side of the throat e to the other the wheel may be run in an opposite direction to the one in which it was revolved previously; but in such case the cutting-edges of the cutters g will be set to cut in just the reverse direction to the one in which they were previously set for cutting. The cutters on one face of the wheel may be set the reverse of those on the other face. The office of these cutters is to enable the wheel to cut its way in and out of the coal-mine, while the cutters on the periphery cut the channel in the mine.

The wheel might be used near the top of a bed of coal, or nearer to the base thereof; and it might be used to cut a channel in a vertical or oblique direction by adjusting it to the railway and frame of the machine, with that purpose in view.

For operating the cutter-wheel, a pinion gear-wheel, D, is fastened upon the shaft C above the platform A¹, and into this pinion a large spur-wheel, E, on a vertical shaft, E', sustained by the two platforms A¹ and A², gears. Upon the shaft E', near the upper part thereof, a worm-wheel, G, is firmly fastened, and this wheel gears with a screw-wheel, F, on a longitudinal shaft, H, sustained by the platform A¹. This shaft H has a worm-thread, I, formed on it, which gears into a screw-wheel, J, of a windlass-drum, K, sustained by the platform A¹.

For transmitting to the gears and cutting-wheel the power of two inclined oscillating engines, L L, mounted upon the main frame A, a crank-shaft, M, is placed across the main frame, and to the crank *m* of this shaft the piston-rods *n n* of the engines are strapped loosely, as shown. The crank-shaft carries a bevel-pinion, M', which gears with a large bevel-wheel, N, on the shaft E' of the spur-wheel E. A tight rope, P, fastened by its respective ends to suitable fixed objects, is coiled around the windlass-drum K, and made to serve for propelling the machine forward as the cutting progresses, and backward after the cutting is completed.

Operation: The machine is brought up to a place in the coal-mine where the coal has been cut away sufficiently for starting the cut or channel under the bed of coal which it is desired to cave in or break down, and the steam or air power is admitted to the engines, which causes the engines to oscillate, and the crank-shaft, gearing, and cutting-wheel to revolve, which latter planes or cuts its way into the mass of coal a distance about equal to half the diameter of the wheel, and during this cutting operation the machine is gradually fed along by reason of the screw-shaft and gears connected with it, imparting a slow revolution to the windlass-drum, and the tight rope causing sufficient friction upon the drum to make it

pull the machine forward. When the channel has been cut the machine is run backward out of the way, and then the miners strike the mass of coal from above and cause it to cave in or fall down.

In the operation of the machine the engines work against one another, and thus the getting on a dead-center is avoided, and jarring and shaking of the whole machine prevented.

The machine described is intended especially as an improvement on my former patent, and is claimed as such.

What I claim as new is—

1. The mining-machine herein described, wherein the shaft carrying the revolving, planing, or cutting wheel is sustained within the main frame by supports entirely above the wheel, and receives its motion from engines by means of gears and shafts supported by, upon, and within, the main frame, substantially as and for the purpose set forth.

2. The revolving planing or cutting wheel, provided with right and left seats for planes or knives, between which seats a recess is formed, substantially as and for the purpose set forth.

ALEXANDER CROMBIE.
